Relza J. Hess and Robert K. Sedgwick,
Chicago, Ill.

Application October 20, 1944, Serial No. 116,133

Term of patent 14 years

(Cl. D63—1)

To all whom it may concern:

Be it known that we, Relza J. Hess and Robert K. Sedgwick, citizens of the United States, residing at Chicago, Illinois, have invented a new, original, and ornamental Design for a Hydraulic Press, of which the following is a specification, reference being had to the accompanying drawings, forming a part thereof, wherein:

Figure 1 is a front elevation of a hydraulic press showing our new design;

Figure 2 is a side elevation thereof;
Figure 3 is a rear elevation thereof; and
Figure 4 is a top plan view thereof.

We claim:

The ornamental design for a hydraulic press, substantially as shown.

RELZA J. HESS.
ROBERT K. SEDGWICK.
